UNITED STATES PATENT OFFICE.

LEWIS OLSON, OF MADISON, WISCONSIN.

WIRE-FENCE BRACE.

No. 804,969.

Specification of Letters Patent.

Patented Nov. 21, 1905.

Application filed July 12, 1905. Serial No. 269,346.

To all whom it may concern:

Be it known that I, LEWIS OLSON, a citizen of the United States, residing at Madison, in the county of Dane and State of Wisconsin, have invented certain new and useful Improvements in Wire-Fence Braces, of which the following is a specification.

This invention relates to wire fences, and more particularly to a brace which is adapted to be placed between the posts in order to reinforce same.

The object of this invention is to produce a device of this character which can be easily and quickly placed in position, which will form a secure brace for the posts, and which will be simple and durable in construction.

With these objects in view the invention consists, essentially, of a rod provided at its respective ends with right and left hand threads and of peculiarly-shaped nuts fitting on the ends of the rod and adapted to be screwed against the sides of the posts.

For a full description of the invention and the merits thereof and also to acquire a knowledge of the details of construction of the means for effecting the result reference is to be had to the following description and accompanying drawings, in which—

Figure 1 is a side view, parts being broken away, showing the application of the device. Fig. 2 is a top plan view of one of the nuts. Fig. 3 is a perspective view of the rod and shows a modification thereof.

Corresponding and like parts are referred to in the following description and indicated in all the views of the drawings by the same reference characters.

The numeral 1 designates two adjacent fence-posts, and 2 the fence-wires. The rod 3 is provided at its opposite ends with right and left hand screw-threads 4 and 5. Peculiarly-constructed nuts 6 fit on the end of the rod 3 and are provided with a head 7, formed with flattened sides for the engagement of a wrench, and a base 8, which fits against the sides of the posts. The base 8 is provided with a number of openings through which spikes 9 are driven into the post in order to prevent the nut from turning loose or slipping out of position upon the posts.

A modification is shown in Fig. 3, in which

the rod 3 is made in two sections, which are slidably connected to enable the length of the rod to be varied according to the distance between the posts. One of the sections is formed with a longitudinal slot, while the opposite section is provided with a bolt which passes through the slot and is employed to clamp the two sections together when the desired adjustment has been attained. This enables one form of the device to be used under all circumstances and does not require special forms for differently-spaced posts.

In order to apply my fence-brace, the length of the rod 3 is adjusted so that the device will fit loosely between the two posts when the nuts 6 are screwed up. The nuts are then screwed out into engagement with the posts until a sufficient amount of pressure has been produced. The spikes 9 are then driven into the posts through the openings in the base of the nuts and effectively prevent the brace from working loose.

Diagonal wires 10 can be employed if desired, and a trussed construction obtained which forms a firm brace for the posts.

Having thus described the invention, what is claimed as new is—

In a device of the character described, the combination of a rod formed in two sections which are slidably connected, one of the sections being provided with a longitudinal slot while the opposite section is provided with a bolt which passes through the slot and is employed to clamp the two sections together when the required adjustment has been attained, said rod being provided at its opposite ends with right and left hand screw-threads nuts fitting on the ends of the rod and formed with faceted heads having an annular flange around the base thereof which fits against the posts and forms a stop-shoulder, and means for securing the annular flange to the posts to prevent the device from slipping out of position or working loose.

In testimony whereof I affix my signature in presence of two witnesses.

LEWIS OLSON. [L. S.]
